UNITED STATES PATENT OFFICE.

CHARLES F. ATTWOOD, OF GRAND RAPIDS, MICHIGAN.

ANTIRATTLER FOR AUTOMOBILE WINDOWS.

Application filed May 27, 1921. Serial No. 473,184.

To all whom it may concern:

Be it known that I, CHARLES F. ATTWOOD, a citizen of the United States, residing at Grand Rapids, in the county of Kent and 5 State of Michigan, have invented certain new and useful Improvements in Antirattlers for Automobile Windows, of which the following is a specification.

My invention relates to improvements in 10 the rubber tips that are used upon the bearing ends of bolts in automobile window and door antirattlers, and its objects are: first, to provide a means whereby the retaining bolt will be held safely against the danger 15 of revolving upon the surface of the glass and becoming loose enough to allow the glass to rattle in its bearings; second, to provide a means whereby it will not be necessary to press the tips too heavily against the 20 glass; third, to provide a means whereby a strong suction may be sustained between the end of the tip and the surface of the glass, and, fourth, to provide a means whereby the tip may be made to revolve freely 25 upon the bolt and thus avert the danger of revolving the end of the tip upon the surface of the glass.

I attain these objects by the construction shown in the accompanying drawing, in 30 which Fig. 1 is a side elevation of the supporting bracket and the compression bolt with the rubber tip shown in section to illustrate, first, its form to provide a nonrevolving bearing upon the surface of the glass, 35 and, second, to show how it is mounted upon the end of the compression bolt. Fig. 2 is a transverse sectional elevation of an automobile window or door frame showing the manner of applying this antirattler and its 40 tip, and, Fig. 3 is a back elevation of the bracket.

Similar reference characters indicate similar parts throughout the several views.

This tip is designed particularly for use 45 upon the bolt and bracket shown in my application No. 466,248, filed May 2, 1921, (design) and I have shown its application herein, in three figures as hereinbefore shown, so as to make the application of the tip, and 50 its action upon the glass, as plainly understandable as possible.

In the drawing 1 represents the part of the sustaining bracket that carries the bolt 4; 2 shows a central offset for receiving the 55 bead upon the edges of the upholstering adjacent to the glass; and 3 represents the

base of the bracket, or the part thereof that is secured to the window or door casing 9. With the bracket 1 secured to the frame 9, as in Fig. 2, the bolt 4 may be revolved, 60 relatively, to the right, and force the tip snugly against the surface of the glass 10, and the opposite surface of the edges of the glass firmly against the flexible packing 11 on the frame 8.

Coming, now, to a detailed description of my invention, the tip 5 is made of some very flexible air tight material, as soft rubber, and has an annular groove in its back opening for the reception of the washer 6, by 70 means of which it is mounted upon the end of the bolt 4 in such a manner that it may be revolved freely thereon, and without danger of its dropping off or becoming disconnected from the bolt. It will be seen that by 75 this arrangement, as soon as the tip 5 begins to press against the surface of the glass it will be held from revolving when the bolt is forcing it against the glass, and the pressure will be directly against the glass.

The outer surface of this tip is dished or hollowed inwardly, as indicated at 7, forming a cup that becomes air tight when the tip is pressed against the surface of the glass, forcing a part of the air out of the cup and 85 forming a vacuous space that will cause the tip to adhere very closely and firmly to the glass and will prevent the bolt from being loosened in its bearings and allowing the glass to become loose in the frame and cause 90 irritating rattling in its frame. This acts a double purpose, first, it prevents the annoyance of rattling windows and doors, and, secondly, it averts, to a large extent, the danger of breaking the glass when driving 95 over rough road beds.

It is to be understood that the wall between the cup 7 and the washer 6 is to be air tight so that when the cup is pressed heavily against the surface of the glass a partial 100 vacuum will be formed so that if the bolt is withdrawn the tip will adhere to the glass until drawn away by the force of the receding bolt drawing upon it.

Having thus fully described my invention, 105 what I claim as new in the art, is:

1. In combination with the bracket and compression bolt in an antirattler for automobile windows, a tip made of a flexible air tight material having a cup indented from 110 the front surface and from the back surface with an air tight wall between said cups, the

cup in the back surface having an annular groove in its walls, and a metal washer anchored in said groove and securely but revolvably mounted upon the end of the bolt and 5 extending thence well over the walls of the cup on the front surface of the pad.

2. In combination with the supporting bracket and the compression bolt of an anti-rattler for automobile windows, a rubber tip 10 made hollow at the back side and having an

annular groove in the walls, the front side of said tip made hollow forming an air tight cup in the front surface, of the tip, a washer securely but revolvably mounted upon the end of the compression bolt, and the tip made 15 to embrace the edges of the washer in the annular groove.

Signed at Grand Rapids, Michigan, May 23 1921.

CHARLES F. ATTWOOD.
